(57) CLAIM

The ornamental design for a pipe with integrated lighter holder, as shown and described.

DESCRIPTION

FIG. 1 is a right top perspective view of a pipe with integrated lighter holder;

FIG. 2 is a left top perspective view thereof;

FIG. 3 is a front elevation view thereof;

FIG. 4 is a top plan view thereof;

FIG. 5 is a bottom plan view thereof;

FIG. 6 is a right elevation view thereof;

FIG. 7 is a left elevation view thereof; and,

FIG. 8 is a right top perspective view with lighter inserted into pipe with integrated lighter holder thereof.

The broken lines in FIGS. 3-8 are directed to environment and form no part of the claimed design while all other broken lines depict portions of the pipe with integrated lighter holder that form no part of the claimed design.
